UNITED STATES PATENT OFFICE.

WILLIAM H. CARY, OF BROCKTON, MASSACHUSETTS, ASSIGNOR TO AVON SOLE COMPANY, OF AVON, MASSACHUSETTS, A CORPORATION OF MASSACHUSETTS.

DESIGN FOR A SHOE SOLE.

Application filed July 3, 1924. Serial No. 10,044. Term of patent 7 years.

To all whom it may concern:

Be it known that I, WILLIAM H. CARY, a citizen of the United States, residing at Brockton, county of Plymouth, State of Massachusetts, have invented a new, original, and ornamental Design for Shoe Sole, of which the following is the specification, reference being had to the accompanying drawing, forming a part thereof.

Fig. 1 is a plan view looking at the bottom or tread surface of a shoe sole embodying my new design.

Fig. 2 is a side view looking toward the edge of the article uppermost in Figure 1.

The sole and heel illustrated in the drawing is for the right foot, and it is of course to be understood that the design is reversed for a sole and heel for the left foot.

I claim:

The ornamental design for a shoe sole as shown.

WILLIAM H. CARY.
